UNITED STATES PATENT OFFICE.

AXEL WALLACE MATTSON, OF QUINCY, MASSACHUSETTS.

PROJECTILE.

SPECIFICATION forming part of Letters Patent No. 702,664, dated June 17, 1902.

Application filed November 20, 1901. Serial No. 83,049. (No model.)

To all whom it may concern:

Be it known that I, AXEL WALLACE MATTSON, a citizen of the United States, residing at 7 Mattson street, Quincy, in the county of Norfolk and State of Massachusetts, have invented certain new and useful Improvements in Projectiles; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to projectiles; and the primary object thereof is to produce a device of this character which will when discharged leave no residue and shell, obviating any liability of the gun-barrel becoming clogged.

A further object of the invention is to produce an accelerating projectile of improved construction.

The invention consists in the novel construction of parts hereinafter fully described and claimed, and illustrated in the accompanying drawings, in which—

Figure 1 is a vertical longitudinal sectional view of a projectile constructed in accordance with my invention, and Fig. 2 is a perspective view of the frame thereof.

1 designates a metallic head provided with an annular flange 2, a central channelled collar 3, and a fulminate 4.

5 designates a cylinder adapted to carry a charge of rapid-burning powder and is constructed of any suitable material and provided on the periphery thereof with a suitable number of radial arms or lugs 6. The cylinder is perforated at intervals throughout its entire length, as at 7, and one end thereof is closed and solid for a portion of its length, as illustrated in Fig. 1 of the drawings, and the opposite end thereof is open and detachably secured in the channel of the collar 3, thus forming a frame for the reception of the materials constituting a projectile. Said cylinder will when the projectile is discharged break away from the head 1, leaving the gun-barrel free of residue and shells.

8 designates a point having a reduced por-

tion 9 and a central recess 10, which receives the solid end of the cylinder 5, to which said projectile is secured.

11 designates a charge of smokeless powder, which is compressed upon the frame and around the reduced portion 9 of the point 8 in any desired manner, and the arms 6 being embedded therein serve to hold it against 60 casual dislodgment.

If desired, the cylinder of compressed powder may be wrapped with a very thin sheet of isinglass, which affords a protection to the powder.

The utility and operation of the device may be explained as follows: The parts being assembled, as illustrated in Fig. 1 of the drawings, by igniting the rapid-burning powder carried by the cylinder 5 through the medium 70 of the fulminate 4 the smokeless powder is simultaneously ignited at different portions of its entire length through the perforations 7 in the cylinder 5, and upon the explosion of the cartridge the point 8 will be discharged 75 from the gun, breaking or withdrawing the frame from its fastening in the collar 3.

It is obvious from the foregoing description, taken in connection with the accompanying drawings, that I produce a projectile which will when discharged leave the gun-barrel free from residue and shells.

Having described my invention, what I claim is—

1. A projectile comprising a firing-head, a 85 stem projecting from the firing-head, and formed with radially-extending lugs, arranged at intervals, and a point carried by the inner end of the stem, and a charge of powder surrounding the stem and having the 90 lugs embedded therein.

2. A projectile comprising a firing-head, a cylinder carrying a charge of rapid-burning powder and projecting from the firing-head, and formed with radially-extending lugs arranged at intervals, and a point carried by the inner end of the cylinder, and a charge of smokeless powder surrounding the cylinder and having the lugs embedded therein.

3. A projectile comprising a firing-head 100 provided with an annular flange and a channelled collar, a cylinder carrying a charge of rapid-burning powder, and perforated at intervals throughout its entire length, and

formed with radially-extending lugs arranged at intervals, one end of said cylinder being open and detachably secured in the channel of said collar, and a point carried by the inner end of said cylinder, and a charge of smokeless powder surrounding the cylinder and having the lugs embedded therein.

4. A projectile comprising a firing-head provided with an annular flange and a channelled collar, a cylinder carrying a charge of rapid-burning powder, and perforated at intervals throughout its entire length, and formed with radially-extending lugs arranged at intervals, one end of said cylinder being closed and solid for a portion of its

length, and the opposite end thereof open and detachably secured in the channel of said collar, a point having a reduced portion and a central recess to receive the solid portion of said cylinder, and a charge of smokeless powder surrounding the cylinder and reduced portion of the point, and having the lugs embedded therein. 20

In testimony whereof I affix my signature in presence of two witnesses.

AXEL WALLACE MATTSON.
